AIR SUPPLY MEANS AND METHOD FOR
CUPOLAS

Roger Stuart Brown, Chicago, Ill.

Application November 9, 1931, Serial No. 574,176

9 Claims. (Cl. 266—14)

This invention relates to improvements in blast furnaces, and more particularly to cupolas. One object is to provide a durable, low cost, hot blast cupola which will melt or smelt with a great economy of fuel, or at a higher temperature, or with both results. For certain compositions, melting at a higher temperature produces a better grade of cast iron, probably due to the complete solution of the carbon at the higher temperature. Another advantage is the possibility of melting a greater proportion or an entirety of steel scrap, without a prohibitive fuel ratio or liability of "freezing" or "bridging". Another advantage is that the much smaller quantity of fuel required results in less sulphur absorption, of paramount importance in melting iron suitable for malleabilizing. The higher temperature, less sulphur absorption, and high percentage of steel scrap possible, enables the making of pearlitic high strength iron, which could heretofore be made only in an electric or air furnace with greatly increased fuel and investment costs. Other advantages will appear from time to time in the specification and claims.

The present application is a continuation in part of my application, Ser. No. 371,156, filed on June 15, 1929.

I illustrate my invention more or less diagrammatically in the accompanying drawings, wherein—

Figure 1 is a vertical section through a cupola of my invention, one half being an outside elevation;

Figure 2 is a horizontal section on the line 2—2 of Figure 1;

Figure 3 is an enlarged horizontal section of a part of Figure 2;

Figure 4 is a section similar to Figure 3 through a variant form;

Figure 5 is a detail of one of the tubes of Figure 4; and

Figures 6 and 7 are partial horizontal sections, each through a variant form.

Like parts are indicated by like symbols throughout the specification and drawings.

Referring to the drawings, A indicates the shell of the cupola which may be supported on any suitable frame or supporting structure A¹, with its bottom plate A² and supporting legs A³. Any suitable closure means may be provided for the hole in the bottom plate A², the details thereof forming no part per se of the present invention. Its hinges are shown as at A⁶ in Figure 1. A⁴ indicates a refractory lining for the shell A.

In order to pre-heat the air I employ any suit-

able inlet pipes B which communicate with the bustle pipe B¹. Assuming the connection with the usual blower, when the cupola is in operation and the blower starts to operate, it forces air through the pipe B and the bustle pipe B¹ for distribution for example through the nipples B³ B⁴, to the heater pipes B⁵. In order to prevent strain on the parts due to variations in temperature I may provide any suitable flexible connecting means, for example the flexible expansion joint couplings B⁶ between the nipples B³ and B⁴. It will be seen from reference to Figures 1, 2 and 3 that the pipes B⁵ are closely adjacent the inner wall of the refractory lining A⁴, said refractory lining being recessed as at A¹⁰ to give room for them. Notwithstanding the close spacings of the pipes B⁵ there is, in the forms shown in Figures 1 to 3, sufficient spacing between adjacent pipes and between the pipes and the refractory lining to permit the heated gases of combustion to contact all sides of each pipe. At least a small quantity of the products of combustion rises between and behind the pipes B⁵, so that they are heated to some extent on the sides and back as well as on the inner face which is in contact with the descending charge and the burned gases passing up through it. The result is a heating effect greater than if the pipes were abutting or heated on only the inside face. Furthermore, heating the pipes on all sides reduces the tendency to warping and growth on the front or inside face of the pipes.

The heated air passes through the pipes B⁵ through nipples B⁷ and B⁸, connected by the flexible connection B⁹, into the hot air bustle pipe B¹⁰.

Communicating with the hot air bustle pipe B¹⁰ are the hot air down-comer pipes C. In order to provide for expansion and contraction these pipes may have interposed therein any suitable flexible or expansion connection C¹. The ends C² of the pipes C communicate with the wind-box or tuyère bustle pipe C³ which may connect directly, or through bootlet boxes C⁴ with one or more rows of tuyères C⁵ C⁶.

One or more connecting pipes D may extend from the cold air header or bustle B¹ to the bustle C³, whereby a controlled fraction of the total air blast may be by-passed, permitting within limits a control of the air blast temperature entering the tuyères. In order to control passage of air through the passages D, I may provide any suitable valve mechanism D¹. Each such valve may be controlled manually but I il-

lustrate diagrammatically any suitable thermo-static control member D².

Referring to Figures 4 and 5, I may employ instead of the pipes B⁵ the pipes E of circular cross-section. Each such pipe, as shown in Figure 5 has an upper integral nipple E¹ and a lower nipple E² which may extend to any suitable flexible or expansion couplings E³.

G indicates the sand bottom for the coke bed. 10 G¹ indicates the melting zone and G² the charging door.

Figure 6 illustrates a variant form in which the air passages H, corresponding to B¹ of Figure 2, are bounded on two faces by the arcs H¹ 15 H², which may be concentric with the axis or center of the cupola. The passages are separated from each other by the arcuately walled spaces H⁴.

Figure 7 illustrates another variant form in 20 which the air passages or ducts J are bounded by the generally plane surfaces walls J¹, being separated by the plane walled passages J². Preferably, as in the form of Figures 2, 6 and 7, the air passages B⁵, H or J, as the case may be, are 25 separated from each other by passages of generally uniform width and are separated from the refractory lining A⁴ by spaces of generally uniform width.

It will be realized that whereas I have 30 described and shown a practical and operative device, nevertheless many changes might be made in the size, shape, number and disposition of parts without departing from the spirit of my invention. I therefore wish my description and 35 drawings to be taken as in a broad sense illustrative and diagrammatic rather than as limiting me to my specific showing. In particular I wish to be understood that I do not limit myself to any particular size, shape or combination 40 of parts except so far as I specifically limit myself thereto in any individual claim.

The use and operation of my invention are as follows:

In employing my invention I pass the air blast 45 of a blast furnace or cupola through an air jacket or series of pipes set around the shaft intermediate the level of the melting zone and the charging door. The length and the location of these pipes may vary with the choice of material and its possible heat resistance. Preferably they do not extend lower than two feet 50 above the upper limit of the melting zone as defined as the point of greatest cutting away of the refractory lining. This might be five or six feet above the upper level of the tuyères. If 55 they are brought down lower it is at the expense of employing very highly heat resisting material for the pipes, with the consequent increase in the initial investment and probably in the maintenance cost. To raise their lower ends much above four feet above the melting zone 60 results in a decrease of efficiency.

An important feature of my invention is that 65 by limiting the total cross-sectional area of the air passages shown at B⁵, I increase greatly the amount of heating effect obtainable from the maximum amount of surface it is possible to place within the cupola. At the same time the heating area of the pipes or pipe walls is increased by the employment of a plurality of individual pipes and passages and by admission of at least some of the heated by-products of combustion at the sides and rear of the passages. 70

By the elimination of tortuous passages or baffling a high heating effect is obtained without

great pressure loss, and hence with a saving in power in running the blower.

Taking the structure as shown for example in Figure 2, I illustrate the passages B⁵ the preferred radial width of which is about 1/28 of the inside diameter of the general cupola passage defined by the inner walls or faces of the members B⁵. In practice I find that a reasonable range of variation in this ratio is from 1/14 to 1/56 of the diameter of the cupola. As small a width as 1/56 is about as small as can be used without getting an excessive power consumption of the blower, and although the heating effect and fuel economy is better, it may usually be preferable to use a greater width of passage. On the other I find that a width of passage greater than 1/14 of the inside diameter of the cupola, while resulting in a minimum of power consumption, reduces the pre-heat and fuel economy. Further, the metal of the pre-heater will run so much hotter than with the smaller ratios, that the maintenance cost is high. 90

In operation the cupola may be made up with a sand bottom coke bed and charges in the usual manner. When the blower starts its operation it forces air through the inlet pipe B. The cold air so supplied fills the bustle passage B¹ and thence passes through the heat passages B⁵. Note that the direction of travel of the air in the passages B⁵ is indicated as parallel with and in the same direction of travel as the by-products 100 of combustion. This arrangement is preferred but I do not wish to be specifically limited thereto except so far as I limit myself in my claims. By passing the air along a path or paths parallel with the ascending gases from the combustion, 110 but passing the air in an opposite direction to the direction of movement of such gases, a somewhat increased pre-heating efficiency is obtained, but at the expense of a greater deterioration of the materials and a resultant necessity of greater investment in heater pipe material of greater heat 115 resistance. As the air enters the relatively restricted passages B⁵ its velocity increases due to the small cross-sectional area of the vertical sections of the heater pipes. Heated by its quick 120 passage through the pipes B⁵, around which the burned or burning gases are flowing, it issues through the nipples B⁷ B⁸ to the hot air bustle pipe C. It thence passes to the wind box C³ and thence to the tuyères C⁵ or C⁶. Inasmuch as it 125 may be advantageous to control to some extent the temperature of the air I provide means, including the passages D and the valve D¹ for bypassing a certain proportion of the cold air from the bustle B¹ to the wind box C³. 130

I find it advantageous to place the air heater sections or passages below the charging door. They are in a position where they are exposed to a practically nonoxidizing atmosphere, due to the excess of carbon monoxide (CO) gas. Therefore they are relatively free from the scaling of material of low heat resistance which takes place in constructions where the air heater sections are placed elsewhere. It is important to properly relate the length of the passages B⁵ to their cross-sectional area in order that the rapidly moving air will pass through a passage of sufficient length and with a sufficient exposed wall area to get the desired heating effect. One method of obtaining the adequate exposed or heating wall area is to 140 heat all sides of the passages, as shown in the accompanying drawings.

One advantage of my construction involving only one straight passage of the air through heat-elements parallel with the movement of the 150

furnace gases, is that it is possible to make the air heating elements without any joints exposed to the high temperature.

I claim:

5. 1. In a hot blast cupola, a cupola member, an air blast inlet passage, a plurality of air pre-heating passages in communication therewith, positioned within said cupola, a charging door for said cupola, said air preheating passages being located substantially below said charging door and means for delivering the air to be pre-heated from said air blast simultaneously to the same end of each of said pre-heating passages, a plurality of tuyères, and means for delivering heated air from the opposite ends of each of said pre-heating passages to said tuyères, the radial width of the passage being in the range of from 1/56 to 1/14 of the interior diameter of the cupola. 80
10. 2. In a hot blast cupola, a cupola member, an air blast inlet passage, a plurality of tuyères and means for pre-heating air for delivery to said tuyères, including a plurality of generally straight pre-heating passage members positioned within said cupola and in general parallelism with each other, and means for maintaining a flow of air therethrough, in parallel, with a like direction of flow in all passages, the radial width of the passages being in the range of from 1/56 to 1/14 of the interior diameter of the cupola. 90
15. 3. The structure of claim 2 characterized in that the pre-heating passage members are spaced from the inner wall of the cupola, the space between the cupola and the passages being open for the passage of the hot gases through the cupola. 95
20. 4. The structure of claim 2 characterized in that the individual pre-heating passages are spaced from each other and from the inner wall of the cupola, the spaces between the individual passages, and between the passages and the cupola being open for the passage of heated gases through the cupola. 100
25. 5. In a hot blast cupola, a cupola member, an air blast inlet passage, an air pre-heating passage in communication therewith, spaced within said cupola and a charging door for said cupola, said air preheating passage being located substantially below the level of said charging door and being spaced radially inwardly from the opposite inner face of the cupola, said passage having a radial width generally equivalent to 1/28 of the interior diameter of the cupola, means for delivering the air to be pre-heated from the air blast to one end of the pre-heating passage, and means for delivering heated air from the opposite end of the passage to the interior of the cupola. 110
30. 6. In a hot blast cupola member, a charging door for said cupola, pre-heating air passage elements, which include a portion positioned within the cupola and centrally spaced inwardly from the opposite inner face of the lining and being located substantially below the level of the charging door, and integral angularly extending end portions at the ends thereof extending outwardly through the cupola wall and removable flexible connection means associated with said ends, positioned substantially without the wall of the cupola. 115
35. 7. In a hot blast cupola, a cupola member, a charging door therefor, a refractory lining therefor, pre-heating air passage members positioned within said cupola and being located substantially below the charging door level and spaced inwardly from the opposite inner face of said lining sufficient to define a gas passage of small but uniform width between the inner face of the refractory lining and the opposed faces of the passages, the passage faces remote from the refractory lining being adapted to contact the charge of the cupola, said passages being generally rectilinear in axial extension, and parallel with the axis of the cupola, the radial width of the passages being in the range of from 1/56 to 1/14 of the interior diameter of the cupola. 120
40. 8. In a hot blast cupola, a cupola member having a charging door, an air blast inlet passage, a plurality of air heating passages in communication therewith, positioned within said cupola member and located substantially below the charging door and spaced centrally inwardly from the inner face of the cupola at that level, said passages having a radial width generally equivalent to 1/28 of the interior diameter of the cupola, means for delivering the air to be pre-heated from the air blast inlet passage to one end of the pre-heating passages, and means for delivering heated air from the opposite end of the passages to the interior of the cupola. 125
45. 9. In a hot blast cupola, a cupola member having a charging door, an air blast inlet passage, a plurality of air preheating passages in communication therewith, and located substantially below the charging door, and spaced centrally inwardly from the inner face of the cupola at that level, said passages having a radial width in the range of from 1/56 to 1/14 of the interior diameter of the cupola, means for delivering air to be pre-heated from the air blast inlet to one end of the preheating passages, and means for delivering preheated air from the opposite end of the passages to the interior of the cupola, said air delivery means being adapted to maintain a flow of air through said passage in parallelism with the path of movement of the heated gases upwardly through the cupola, and in the same direction. 130
50. 60. 65. 70. 75. 80. 85. 90. 95. 100. 105. 110. 115. 120. 125. 130. 135. 140. 145. 150.
